UNITED STATES PATENT OFFICE.

ROBERT GALLOWAY, OF BUFFALO, NEW YORK.

SUCTION APPARATUS.

1,113,426.

Specification of Letters Patent. Patented Oct. 13, 1914.

Application filed August 9, 1912. Serial No. 714,274.

To all whom it may concern:

Be it known that I, ROBERT GALLOWAY, a citizen of the United States, and resident of Buffalo, in the county of Erie and State of New York, have invented certain new and useful Improvements in Suction Apparatus; and I do hereby declare the following to be a full, clear, and exact description of the same, reference being had to the accompanying drawings, forming part of this specification, and to the figures and letter of reference marked thereon.

This invention relates to improvements in apparatus for vacuum cleaning especially designed for use in connection with a low pressure water system, the objects of the invention being to provide a device simple in construction and in which the necessity of employing packing glands and adjusting screws, etc. is entirely avoided.

To these ends the invention consists in certain novel details of construction and combinations and arrangement of parts all as will be now described and the particular features of novelty pointed out in the appended claims.

In the accompanying drawings, wherein is illustrated the preferred embodiment of the invention, Figure 1 is a sectional view of an apparatus embodying the present invention; Figs. 2 and 3 are detail views of the nozzle alone.

Like letters of reference in the several figures indicate the same parts.

Referring to the drawings, the letter A indicates a pipe fitting formed at its upper end with an extension A' adapted to be connected with a faucet or spigot, not shown, of an ordinary water supply system. A branch pipe B, through which the suction is to be created, enters the fitting A intermediate the supply and discharge ends, the passages in the fitting and branch preferably gradually merging toward the discharge end or head.

In order to secure the most efficient action, it is necessary that the column of water be broken up into a spray or fine particles. To accomplish this, in the present invention, a nozzle C of peculiar construction is located in the pipe A, immediately above the branch pipe B. This nozzle consists preferably of a hollow cylindrical casing fitted within the pipe A and having in its opposite ends alined openings c, c'. The ends of the cylindrical casing or nozzle C form parallel

diaphragms which are in immovable or non-adjustable relation and the opening c, c' therethrough are of the same area with cylindrical walls in alinement with each other. The nozzle C fits tightly within the pipe A forming a water tight joint, thus doing away with the necessity of packing of any kind. At the lower end of the pipe B, is a trap D, having baffles d d, arranged out of alinement with each other to form a trap water sealed, such construction aiding in securing a more perfect vacuum, as it prevents the return of air from the discharge end. It will be noted that the lower wall of the trap is curved or downwardly inclined whereby the discharge of the air and water is accelerated thus preventing back flow of air and back pressure on the suction nozzle.

To give the best results the inner cross sectional area of the pipe or fitting A below the branch B should be of proper size and shape to suit the water pressure, and means is provided in the present apparatus to adapt the device for use under various pressures. For this purpose a throat piece E is provided which consists of a pipe section or liner having a flaring upper end which is fitted removably within the pipe A. Various sizes of these throat pieces may be provided and these can be readily put in place by simply removing the return trap and slipping the throat piece into the pipe A.

The effect of a nozzle of the construction described so far as I am able to determine is to so subdivide the stream that it will carry with it a large volume of air and produce a higher vacuum with a lower water pressure than has been secured with nozzles previously in use. The reasons for the results accomplished are largely speculative, but it is believed that the two diaphragms formed by the heads of the nozzle and having alined central apertures cause such a tumbling action of the water that it separates completely into minute drops as it issues from the nozzle while still retaining its momentum and velocity and thereby entrains a larger volume of air which is swept through the reduced passage below the branch pipe or air chamber and its return effectually prevented by both the following water and air and by the bottom trap. The alined openings in the separated diaphragms are believed to give direction to the issuing stream as well as to induce

the tumbling action which effects the complete subdivision of the stream into a spray as it passes through the air chamber.

While the nozzle has been shown and described in connection with a vacuum cleaning or suction apparatus it has been found that it forms a very efficient spray nozzle for spraying fruit trees, etc.

Having thus described my invention, 10 what I claim as new and desire to secure by Letters Patent of the United States, is:

1. In a suction apparatus, the combination with a fitting adapted to be connected with a supply system and having a suction branch communicating therewith intermediate the pressure and discharge ends, of a spray nozzle located within the fitting at the pressure side of the opening of the suction branch and embodying two parallel 20 diaphragms in immovable relation with a distance chamber between and having central openings therein with cylindrical walls in alinement with each other and whose areas are less than the areas in cross section 25 of the adjacent parts of the fitting and the distance chamber.

2. In a suction apparatus, the combination with a fitting adapted to be connected to a supply system and having a suction branch, of a nozzle consisting of a chambered casing having alined inlet and discharge openings in its opposite ends whose areas are equal and less than the areas in cross section of the adjacent parts of the 30 fitting and the chambered casing, said nozzle being located within the fitting at the pressure side of the suction branch.

3. In a suction apparatus, the combination with a fitting adapted to be connected 40 with a supply system and having a suction branch pipe, of a spray nozzle consisting of a chambered casing having inlet and discharge openings in its opposite ends whose areas are less than the areas in cross section 45 of the adjacent parts of the fitting and the chambered casing, the water sealed trap attached to the discharge end of the said fitting through which both air and water are continuously discharged said trap having two inside baffle plates arranged zig-zag 50 whereby the back flow of air into the suc-

tion chamber is prevented and a more efficient vacuum maintained.

4. In a suction apparatus, the combination with a fitting adapted to be connected with a supply system and having a suction branch pipe, of a spray nozzle consisting of a chambered casing having inlet and discharge openings in its opposite ends whose areas are less than the areas in cross section 60 of the adjacent parts of the fitting and the chambered casing, the removable throat piece fitted within the said fitting below the suction branch pipe, the water sealed trap attached to the discharge end of the said fitting through which both air and water are continuously discharged said trap having two internal baffle plates arranged out of alinement whereby the back flow of air to the suction nozzle is prevented and a more 65 efficient vacuum secured.

5. In a suction apparatus, the combination with a fitting adapted to be connected to a supply system and having a suction branch, of a nozzle located within the fitting and consisting of a chambered casing having two parallel diaphragms in immovable relation to each other and having alined inlet and discharge openings therein whose areas are equal and less than the areas in 75 cross section of the adjacent parts of the fitting and chambered casing.

6. In a suction apparatus, the combination with a fitting adapted to be connected to a supply system and having a suction 80 branch pipe, of a spray nozzle consisting of a chambered casing having inlet and discharge openings in its opposite ends whose areas are less than the areas in cross section 85 of the adjacent parts of the fitting and the chambered casing, a water sealed trap attached to the discharge end of the aforesaid fitting and having a curved or inclined lower wall whereby the discharge of air and water will be accelerated and back flow of 90 air into the suction chamber and back pressure on the suction nozzle will be prevented thereby creating a more efficient suction.

ROBERT GALLOWAY.
